US0D1110852S

(12) **United States Design Patent** (10) **Patent No.:** **US D1,110,852 S**
Aboabdo (45) **Date of Patent:** **** Feb. 3, 2026**

(54) **BOTTLE**(71) Applicant: **Chubby Gorilla, Inc.**, Fullerton, CA (US)(72) Inventor: **Ibrahiem H. Aboabdo**, Yorba Linda, CA (US)(73) Assignee: **Chubby Gorilla, Inc.**, Fullerton, CA (US)(**) Term: **15 Years**(21) Appl. No.: **29/910,733**(22) Filed: **Aug. 23, 2023****Related U.S. Application Data**

(60) Division of application No. 29/765,561, filed on Jan. 8, 2021, now Pat. No. Des. 999,637, which is a continuation of application No. 29/614,048, filed on Aug. 15, 2017, now Pat. No. Des. 908,500, and a continuation of application No. 29/610,633, filed on Jul. 13, 2017, now Pat. No. Des. 907,500, said application No. 29/614,048 is a continuation of application No. 29/610,633, filed on Jul. 13, 2017, now Pat. No. Des. 907,500.

CLAIM

The ornamental design for a bottle, as shown and described.

DESCRIPTION

FIG. 1 is a top perspective view of a first embodiment of a bottle, showing my new design.

FIG. 2 is a partially enlarged view thereof, taken from FIG. 1.

FIG. 3 is a front view thereof.

FIG. 4 is a rear view thereof.

FIG. 5 is a first side view thereof.

FIG. 6 is a second side view thereof.

FIG. 7 is a top view thereof.

FIG. 8 is a bottom view thereof.

FIG. 9 is an exploded perspective view thereof.

FIG. 10 is an exploded view thereof.

FIG. 11 is a cross-sectional view thereof, taken along line 11-11 in FIG. 1.

FIG. 12 is a top perspective view of a second embodiment of a bottle, showing my new design.

FIG. 13 is a partially enlarged view thereof, taken from FIG. 12.

FIG. 14 is a front view thereof.

FIG. 15 is a rear view thereof.

FIG. 16 is a first side view thereof.

FIG. 17 is a second side view thereof.

FIG. 18 is a top view thereof.

FIG. 19 is a bottom view thereof.

FIG. 20 is an exploded perspective view thereof.

FIG. 21 is an exploded view thereof.

FIG. 22 is a cross-sectional view thereof, taken along line 22-22 in FIG. 12.

FIG. 23 is a top perspective view of a third embodiment of a bottle, showing my new design.

FIG. 24 is a partially enlarged view thereof, taken from FIG. 23.

FIG. 25 is a front view thereof.

FIG. 26 is a rear view thereof.

FIG. 27 is a first side view thereof.

FIG. 28 is a second side view thereof.

FIG. 29 is a top view thereof.

FIG. 30 is a bottom view thereof.

FIG. 31 is an exploded perspective view thereof.

FIG. 32 is an exploded view thereof.

FIG. 33 is a cross-sectional view thereof, taken along line 33-33 in FIG. 23.

FIG. 34 is a top perspective view of a fourth embodiment of a bottle, showing my new design.

FIG. 35 is a partially enlarged view thereof, taken from FIG. 34.

FIG. 36 is a front view thereof.

FIG. 37 is a rear view thereof.

FIG. 38 is a first side view thereof.

FIG. 39 is a second side view thereof.

FIG. 40 is a top view thereof.

FIG. 41 is a bottom view thereof.

FIG. 42 is an exploded perspective view thereof.

FIG. 43 is an exploded view thereof; and,

FIG. 44 is a cross-sectional view thereof, taken along line 44-44 in FIG. 34.

The second embodiment is shown with a symbolic break in its length, represented by break lines. The appearance of any portion of the article between the break lines forms no part of the claimed subject matter.

All features in broken lines are for the purpose of illustrating environmental structure and form no part of the claimed subject matter.
